UNITED STATES PATENT OFFICE.

FRANK L. DODGSON AND WINTHROP K. HOWE, OF BUFFALO, NEW YORK, ASSIGNEES TO
GENERAL RAILWAY SIGNAL COMPANY, OF BUFFALO, NEW YORK, A CORPORATION
OF NEW YORK.

RAILWAY SIGNALING APPARATUS.

No. 872,613.

Specification of Letters Patent.

Patented Dec. 3, 1907.

Application filed November 27, 1905. Serial No. 289,292.

To all whom it may concern:

Be it known that we, FRANK L. DODGSON and WINTHROP K. HOWE, citizens of the United States, residing at Buffalo, in the 5 county of Erie and State of New York, have invented a new and useful Improvement in Railway Signaling Apparatus, of which the following is a specification.

Our invention relates to railway signaling, 10 and more particularly to train brake control in connection with a signal.

The object of our invention is to provide means for applying the air-brakes on a train automatically and without the let or hindrance of the engineer if he attempts to pass 15 a signal when set in the stop position; also to so stop a train in like manner in the event of any break-down of any of the mechanism or the cessation of current, from any cause, 20 which controls the air-control mechanism, as hereafter described. We are aware that a number of devices have been intended for a similar purpose, such, for example, as mechanical trips placed upon the locomotive or 25 car in such a way that, when they come in contact with an obstruction raised in the track-space, they will open a valve in the train-pipe, thus setting the air-brakes. In other devices this end is accomplished by 30 means of electrical contacts on the locomotive or car or the track and electro-magnetic means for controlling a valve in the train pipe. We refer to these two classes of 35 devices in order to point out the defects which we overcome and to show wherein our invention meets the fundamental requirements of railway signaling as such requirements have not been met heretofore.

The mechanical devices above referred to 40 are objectionable in that they have the fundamental objection of physical contact between a moving and a fixed point; and also that the moving piece or trip on the engine or car may be interfered with by ice, snow or 45 other obstruction on the track, and may thus apply the air-brakes when it is not intended they should be applied. The prior electrical devices above referred to are objectionable in that their operation depends upon the application of current and also upon the actual 50 making of physical contact.

In our invention we have overcome all of these objections by dispensing with all mechanical or electrical contact between the

apparatus on the track and the apparatus on 55 the locomotive or car; and furthermore we have met the objection of operativeness dependent upon current by depending entirely upon the absence of current for setting the air-brakes—that is to say, current must be 60 present in order to prevent the brakes from being applied, and a break in any of the parts or cessation of current from any cause will cause the brakes to be applied. Thus 65 our invention avoids the objection of physical contact between train and track apparatus, and meets the fundamental requirement of railway signaling, that the normal position of the parts must be the "stop" position.

70
In the following description of our invention we shall show the same as employed in connection with a visual signal. It will be understood, however, that the invention has a much wider field of use, as, for example in 75 connection with a switch-box, a draw-bridge lock, at a grade crossing and the like; and while, for brevity and clearness we have, in the claims, employed the term "signal", it will be understood that we do not intend to 80 so limit ourselves, but claim broadly the general adaptation of our invention to switching and signaling purposes.

85
Referring to the drawings herewith, in which like characters of reference indicate corresponding parts, Figure 1 represents diagrammatically a side elevation of our invention. Fig. 2 is a diagrammatic plan showing the relation of the signal and the device which is placed adjacent to the track. Fig. 90 3 is a detail plan view of said last mentioned device. Fig. 4 is a view similar to Fig. 1 of a modified form of our invention.

95
R, R, represent the rails of the track; W, W, the wheels of a locomotive or car truck, S a signal, P the train-pipe, and V a valve in said train-pipe. Referring first to Figs. 1 to 3, 1 is a magnet of special construction which is carried on the frame of the truck of a car or a locomotive, preferably overhanging the 100 space between the rails, R, R, as shown (although it will be understood that this magnet may depend outside the rails when its coating member is so placed) 2 is a device hereafter more fully described, so placed 105 between the tracks that the magnet 1 will pass directly over it, in close proximity, but without touching it.

We will first describe the several elements relating to the magnet 1.

The magnet 1 comprises pole-pieces 3 and 4, which are large in proportion to the core 5, which carries the windings 6. The windings 6 are connected permanently to a source of electric energy 7 carried by the car or locomotive, by wires 8, 9, 10 and 11. Pivoted to the pole-piece 4 is an armature 12, which carries a contact piece 15, capable of making electrical connection between contact points 13 and 14. The proportion of the winding 6 and other parts of the magnet 1 are such that, under normal conditions, enough lines of force come through the armature 12 to hold it in contact with pole-piece 3; but when any mass of iron is brought in proximity to the lower parts of the pole-pieces 3 and 4, some lines of force will be diverted from armature 12 and pass through said mass of iron, thus causing the armature 12 to fall away from the pole-piece 3 and break the contact between the points 13 and 14. The contact-point 13 connects with battery 7 by wires 16 and 11; and contact point 14 connects with the opposite pole of battery 7 through wire 17, coil of solenoid 18, and wires 19 and 8. The solenoid connects with the stem of valve V in such manner that, when the solenoid 18 is energized, the valve V is closed thereby, and when said solenoid 18 is deenergized the valve V automatically opens.

Referring now to the device 2, placed adjacent to the track, within a non-magnetic casing 22 is an iron plate 20. This plate is pivoted to arms 21, 21, which are pivoted at their lower ends to the casing 22 and which are medially pivoted to a bar 23. The bar 23 is pivotally connected to the blade or other moving part of the signal S (see Fig. 2) by rod 24, bell-crank lever 30, rod 29, bell-crank lever 28, rod 27, lever 26 and rod 25. The plate 20 is shown in "proceed" position in full lines and in "stop" position in broken lines. It will now be seen that, if the plate 20 is raised by movement of the signal S to the "stop" position, it will be brought into the field of the magnet 1.

50 The operation is as follows: The magnet 1 being free from external influence, the battery 7 energizes the pole-pieces 3 and 4, and the armature 12 is raised to close points 13 and 14 with plate 15. This closes another circuit including the magnet or solenoid 18, the current flowing through both circuits at the same time, and the magnet 18 acts to close the valve V. This condition continues until attempt is made to pass a signal set at 60 the "stop" position, or until a break in the apparatus occurs. If such disregard of a signal occurs, the plate 20 being in the raised position, the magnet 1 will be affected thereby to deprive the armature 12 of sufficient lines of force to cause the plate 15 to fall

from electrical connection with the points 13 and 14. This will deenergize the magnet 18, and the valve V will automatically open and put on the air. In like manner any break in the apparatus carried by the train 70 will result in opening the valve V, and any break in the signal mechanism will produce a like result, since normality depends upon working condition and flow of current.

Referring now to Fig. 4, we have there 75 shown our invention adapted to the employment of a governing current of the alternating type. It will be seen that the general construction is the same as above described except as to the features which we will now 80 point out. 7' is a source of alternating current which is in permanent circuit with a winding 6' on the core 5. Instead of an armature 12 we employ a second winding 31 on the core 5, and this winding is in permanent 85 circuit with a relay magnet 32. This relay 32 has an armature 33 spring-held out of contact with the core of the relay 32, and capable of making electrical connection with a contact piece 34 under the conditions hereafter 90 described. Contact of the armature 33 with the piece 34 closes a circuit including a battery 35, wire 36, armature 33, contact 34, wire 37, winding of magnet 18, and wire 38 to battery 35. It will now be seen that, under 95 ordinary conditions, the current flowing through the winding 6' will set up a feeble current in the winding 31—that is, the two windings will act as the primary and secondary of a transformer, developing sufficient 100 energy in the relay 32 to lift the armature 33 against its spring into electrical connection with the contact piece 34, but not enough to lift said armature 33 clear of the contact 34 and against the core of the relay 32. If, 105 now, a conductor, such as the plate 20, is brought into the fields of the pole-pieces 3 and 4, the flow will be materially increased and a much more powerful current will be set up in the coil of the relay 32. This will result in 110 sufficient energization of said relay 32 to cause the armature 33 to break contact with the plate 34, thus deenergizing the magnet 18 and allowing the valve V to automatically 115 put on the air.

It will thus be seen that the functions and general construction of the two forms of our apparatus are the same, the one being adapted to a continuous governing current and the other to an alternating governing current.

Having thus described our invention, what we claim is:

1. In combination with a signal and a brake system of a railway train, electromagnetic means carried by said train for normally holding said brake system inactive, and means actuated by said signal comprising a conductor capable of diverting the lines of magnetic force from the governing magnet 125

of said electro-magnetic means for rendering said electro-magnetic means inactive, when said signal is in the "stop" position and causing said brake system to act.

- 5 2. In combination with a signal and a brake system of a railway train, electromagnetic means carried by said train for normally holding said brake system inactive, a magnet, an electric switch governing said 10 electro-magnetic means, a source of electric energy, a magnetic conductor and means actuated by said signal for moving it in and out of the plane of the field of said magnet, said magnet having its poles and helix so proportioned as to cause it to release said electric switch when said conductor is in its magnetic field.

15 3. In combination with the brake system of a railway train, a train stop comprising a

valve biased to the position of air on, electro- 20 magnetic means for normally overcoming such bias, an electro-magnet, an electric switch governed by said magnet and governing said first-mentioned electro-magnetic means, a source of electric energy; and a 25 magnetic conductor adjacent to the tracks and means for moving it in and out of the plane of the magnetic field of said magnet, said magnet having its poles and helix so disproportioned as to release said switch when 30 said magnetic conductor is in its field.

In testimony whereof, we have hereunto set our hands in the presence of two witnesses.

FRANK L. DODGSON.
WINTHROP K. HOWE.
